(57) **CLAIM**

I claim the ornamental design for a solar-powered cell phone, as shown and described.

DESCRIPTION

FIG. 1 is a front view of the solar-powered cell phone.

FIG. 2 is a rear view thereof.

FIG. 3 is a left side view thereof.

FIG. 4 is a right side view thereof.

FIG. 5 is a top view thereof.

FIG. 6 is a bottom view thereof; and,

FIG. 7 is a perspective view thereof.

1 Claim, 5 Drawing SheetsFIG. 1

FIG. 2

FIG. 3

FIG. 4

FIG. 5

FIG. 6

FIG. 7
